(57) **CLAIM**

The ornamental design for a door for clothes management apparatus, as shown and described.

DESCRIPTION

FIG. 1 is a perspective view of a door for clothes management apparatus showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view showing the design in use;

FIG. 9 is a perspective view thereof showing the state in which the pants press has been opened;

FIG. 10 is a front view of FIG. 9;

FIG. 11 is a left side view of FIG. 9;

FIG. 12 is a right side view of FIG. 9;

FIG. 13 is a top plan view of FIG. 9; and,

FIG. 14 is a bottom plan view of FIG. 9.

The broken lines are for illustrative purposes only and form no part of the claimed design.
